UNITED STATES PATENT OFFICE.

WINSLOW R. PARSONS, OF CHICAGO, ILLINOIS.

BOOK OR BOX LIKE FORM SAVINGS-BANK.

1,193,598.

Specification of Letters Patent.

Patented Aug. 8, 1916.

Application filed May 31, 1912. Serial No. 700,616.

To all whom it may concern:

Be it known that I, WINSLOW R. PARSONS, a citizen of the United States, and resident of Chicago, in the county of Cook and State of Illinois, have invented certain new and useful Improvements in Book or Box like Form Savings-Banks, of which the following is a full, clear, and exact specification.

10 This invention relates to improvements in book or box-like form savings banks composed entirely of sheet metal, except possibly a cover of leather or other material commonly employed for binding books in which it is either desirable or necessary to form separately and subsequently lock together the imitation book edges with the book-cover with one edge hinged and provided with a lock and key for access to the 20 contents of the book-like bank.

15 The prime object of this invention broadly stated is to provide means whereby on assembling the cover and the edges of a book-like bank, their locking devices are not only 25 concealed from external view and from accidental detachment but that the pieces of metal of which the book edge is composed cannot be disconnected from the cover by anyone, except by a hand implement, and 30 then only by one who is familiar with the method of assembling them in their operative positions.

35 A further object is a simple and effective means opposing the coin receiving slot preventing the withdrawal of a coin from the slot after it has once been but partly projected into the coin holding receptacle.

With these ends in view, my invention finds embodiment in certain features of novelty in the construction, combination and arrangement of parts by which the said objects and certain other objects are herein-after attained, all as fully described with reference to the accompanying drawings, 45 and more particularly pointed out in the claims.

In said drawing: Figure 1 illustrates a perspective view of a book-like savings bank, in which my invention finds embodiment. Fig. 2 is a section on the line 2—2 of Fig. 1 looking in the direction of the arrows. Fig. 3 is a transverse section on the line 3—3 of Fig. 4 looking in the direction of the arrows. Fig. 4 is a section on the line 4—4 of Fig. 1 looking in the direction of the arrows. Fig. 5 is a detail perspective view of the plate

illustrated in cross section of Fig. 3. Fig. 6 is a sectional elevation with dotted lines indicating the position of the hinged book edge in moving it to an open position. Fig. 7 shows a transverse section on the line 7—7 of Fig. 6. Fig. 8 is a transverse section of the coin gripping device opposing the coin receiving slot, and Fig. 9 is a detail perspective of one of the opposing serrated blades 65 gripping the coin in its passage through the coin receiving slot to the bank receptacle. Fig. 10 is a perspective view of the locking strip or plate detached.

Similar characters of reference indicate 70 the same parts in the several figures of the drawing.

10—10 indicates the opposing covers, and 11 the back of a bank in book form, the cover of which is struck from a single sheet 75 of metal bent upon itself adjacent its back portion in imitation of the hinged joint between the covers and their back, and thereby forming opposing longitudinal grooves 12—12 adapted to receive and hold 80 against lateral displacement a short plate 13 inserted between them, and which may be additionally secured in place by a hand punch (not shown), simultaneously upsetting the metal of the back (not shown), and 85 the plate as indicated at 14, the plate being provided with a split lug forming two tongues 15—15 adapted to register with notches 16—16 in a spring metal strip 17 extending longitudinally, substantially from 90 one end to the other of the book.

Notches 16—16 are toward one end of an elongated slot in the strip 17, which slot has an enlargement 18 at its opposite end through which to pass the split lug 15 to 95 engagement with the notches, the edges of the strip at a point between this enlargement and the notches being bent outwardly beyond the concave surface of the strip to form a converging bearing surface 19 en- 100 gaging the underside of and directing the split lug to the notches, or in other words springing the plate so that the split lug gradually depresses the plate until the split lug registers with the notches. 105

One end of the spring plate 17 is provided with an outward, and somewhat sharply inclined flange 20, the other end of the plate being provided with a slot 21 forming the keeper for the bolt of a lock 110 hereinafter described, the end of the plate beyond this slot being gradually inclined

as indicated at 21^a to hold the keeper slot away from the metal edge of the book, and give a correspondingly great depth to the keeper and range of flexibility of the strip 5 17 when flexing it to engagement with the notched lug.

Between the extreme ends of the plate 17 and upturned therefrom are opposing lugs 22—22 and 23—23 forming side bearings 10 for the strip so to speak, against the adjacent bead in the book back resulting from the formation of the grooves 12—12, the purpose of these lugs being to prevent any portion of the edge of the strip from entering either of these grooves and as guides 15 directing the strip in its movement toward locking position and at the same time maintaining the keeper slot in perfect register with the lock bolt.

20 Forming the longitudinal imitation side edge of the book is a metal strip 24, preferably of brass for imitating a gilt edge book, from which is bent one end edge 25 of a book, the free end of which end edge terminates in a hook 26, adapted to be interlocked with the flange 20 on the plate 17. The longitudinal book edge strip 24 is provided about midway its length adjacent its edges with opposing hooks 27 bent from the strip 30 with their outer faces flush with the edge thereof, so that the strip may fit close against the opposing faces of the cover, the bearing faces of these hooks being preferably slightly inclined so that the hooks may 35 wedge when engaged with a plate 28, spaced apart and connecting the free edges of the cover plates, as indicated in Fig. 6, when the book edge plate is in its operative position.

40 End edge plate 25 is provided with opposing lugs 29, likewise struck therefrom and flush with the edges and extending at a right angle to the face of the edge plate, which lugs are adapted to register with and 45 engage slots in a metal strip 30, spacing and connecting the opposing covers of the book at that point, the end of which strip adjacent the edge plate 24 is provided with an inner bent plate 31 sustaining the corners 50 of the covers without interfering with the moving of the bent plate forming the top and bottom book edges to and from its operative position.

In addition to the cover sustaining members 28 and 30, and also a sustaining plate 55 or post 30^a there are also toward the upper end of the book structure hook shaped opposing lugs 32 struck from the metal of the longitudinal edge piece and bent to a position so that their outer faces are flush with the edges of the plate adapted to engage and hook over upon a book cover sustaining plate or post 33, the stud having formed therewith a projection or lug 34 forming the 60 bearing of a pivot 35 on which is hinged the 65

slotted cover strip 37 forming the top edge of the book, by means of (see Figs. 6 and 7), opposing lugs 38—38 which lugs are bent from the edge of the cover strip 37.

The edge cover strip 37 is of a width 70 slightly less than the distance between the covers 10—10 between which to insert and hold, as hereinafter described, a binding, when one is employed, and is provided with a coin slot 39, preferably of a length and 75 width for inserting a silver dollar, as well as smaller coins of less value. At each side of and extending lengthwise of this coin slot are angle plates 40—40 of spring metal provided with a number of transverse slots 80 41 forming spring tongues 42 in the free end of each of which are two or more saw like teeth 43, from the base of which is bent at a right angle a flange 44 forming the base support of the teeth by which to secure 85 them to the underside of the hinged cover strip 37 by means of opposing lugs 45 bent from and flush with the edges of the cover strip 37, and over upon opposing flanges 46 of a slotted casing 47, between which and 90 the strip 37 the flanges 44 of the teeth are clamped and held, the points of the teeth projecting through the slot 48 of the casing as indicated in Fig. 8, whereby the longitudinal walls of the slot 48 operate as a stop 95 limiting the distance at which the teeth may be forced apart by a coin inserted between them, the limit of which thickness as before indicated, is preferably that of the thickness of a silver dollar.

In arrangement the opposing teeth 43 preferably alternate, and project between each other in order to prevent the insertion of anything less hard than coin, but principally that when forced apart by a coin their 105 grip shall be sufficient to prevent the withdrawal of the coin after any part of it is once inserted between the teeth. On the underside of the hinged edge strip 37 is a lock casing 49 provided with outwardly projecting flanges 50 by means of which it is secured to the strip 37 by means of opposing lugs 51 bent from the strip 37 and flush with the side edges thereof, as are the lugs 45 at the coin slot in the same strip, at both ends. 110

Confined within the casing 49 is a lock mechanism (not shown) of any common or preferred construction, the circular barrel 52 of which projects through the strip 37, and is provided with a slot 53 registerable 120 with a slot 54 in the strip 37 through which to pass a key (not shown), for operating the lock, the lock bolt 54^a of which (see Fig. 6), projects through the slot 21 in the spring plate 17, holding the latch-bolt in its locked 125 position, and in which position the bolt projects through and beyond the spring plate 17 by reason of the bent end 21^a thereof.

When a binding 55, such as leather, cloth or other material commonly employed for 130

book binding purposes is used, it is preferably of one piece cemented to the back and covers and sustained over their edges as indicated at 56, so as to project, (see Figs. 1, 5 2, 4 and 7) inwardly beyond the side edges and ends of the edge strips 24 and 37 so that these overlapping edges may be and are clamped between said edges, and the cover, and thereby conceal the edges of the binding, by giving not only the binding but the gilt edges a finished and attractive appearance as closely imitating as may be a bound book having gilt edges.

For the purpose of automatically holding 15 the hinged cover in a side open position, there is coiled upon a pivot 35 a spring 36 one end of which is fixed to the pivot and the other projected, (see Fig. 6) so as to have an end bearing against the inner face 20 of the upper end of the side edge strip 24, which spring, however, is sufficiently yielding to permit the moving of the top edge strip to its locked position.

From the foregoing it will now be understood 25 that an important feature of my invention is that of having in book-like form a savings bank in which all of the parts are metal save a binding, if one be employed, with the cover and back integral, provided 30 with separate side edges simulating that of a gilt edge book when closed, in which the opposing separate covers are rigidly and accurately sustained in their operative position, the parts forming the edges and the 35 cover being so constructed and connected that they may be quickly assembled and locked together in such a manner and by such means that one unfamiliar with the method of the locking cannot possibly separate them while at the same time access may 40 be had to the receptacle by means of a lock and key and a coin may not be withdrawn after being but partly inserted through the receiving slot into the receptacle, and in 45 this connection it may also be remarked that my invention is not limited to the special details of construction herein shown and described, so long as they provide for securing the results herein recited.

50 The cover sustaining plates or posts 28—33—30 and 30^a are each provided at their opposite ends, (see Fig. 1) with two or more lugs 30^b, projected through and upset flush with the outer faces of the covers 55 whereby they are locked to the covers and as a result the covers are not only uniformly spaced, but rigidly and permanently sustained while at the same time the lugs being of the same metal as the covers so blend 60 therewith that they are hardly distinguished from the covers, and which, of course, gives the covers a very slight appearance. As the cutting off of the edges of the book cover would give it more the appearance of a box, 65 my invention is, therefore, not limited in its

application to a bank specifically of book form.

Having described my invention, what I claim and desire to secure by Letters Patent is:

70 1. A book-form savings bank comprising in combination, a back and covers bent from a single piece of metal, a strip forming the edges of the book, a pivotal joint in said strip and means at the back edge of the book connecting and locking said strip at opposite ends respectively to the back and covers.

75 2. A book-form savings bank comprising in combination a back and covers bent from a single piece of metal, a strip of metal forming side edges therefor, a sliding latch plate detachably locking said strip to the back of said covers.

80 3. A book-form savings bank comprising in combination a back and covers bent from a single piece of metal, a bent strip of metal forming two side edges thereof, a sliding latch plate provided with a slot, and a lug secured to the back engaging the slot, for 85 detachably connecting said strip with the covers.

85 4. A book-form savings bank comprising in combination a back and covers bent from a single piece of metal, a bent strip of metal forming two side edges thereof, a slideable 90 spring latch plate and a lug secured to the back detachably connecting said strip and plate with the back of the covers.

95 5. A book-form savings bank comprising in combination a back and covers bent from a single piece of metal, a bent strip of metal forming two side edges thereof, a hook connecting said strip and cover, a lug and a sliding spring latch plate provided with a 100 slot detachably locking said hook against disengagement, and the strip to the covers.

105 6. A book-form savings bank comprising in combination a back and covers bent from a single piece of metal, a bent strip of metal forming two side edges, a strip jointed thereto forming the other side edge, an internal latch plate removably locked to the back and interlocked with one end of the bent edge strip internally of the coin receptacle of the book, a slot in the opposite end of said latch plate, and a lock on the jointed edge strip, the bolt of which is adapted to be projected through and withdrawn from said slot.

110 7. A book-form savings bank comprising in combination a back and covers bent from a single sheet of metal, a jointed metal strip forming the three book edges between the covers, a spring metal plate provided with 115 an elongated slot having notches toward one end and a split lug permanently secured to the back of the cover provided with teeth adapted to engage and removably lock the plate to said back, and means for removably 120 125 130

connecting said metal plate with both ends of the jointed edge strip.

8. A book-form savings bank comprising in combination a back and opposing separated covers, means rigidly locking said covers in their operative spaced position, longitudinally opposing grooves and beads therein between the back and covers, a split lug plate, the edges of which are confined 10 between said grooves against lateral displacement, a spring metal locking plate in a plane inwardly beyond said grooves provided with lugs bearing against said beads, and provided with a slot for removably en- 15 gaging and locking said plate to the split lug plate, said locking plate being provided toward one end with a slot and its opposite end with a hook bent therefrom, an edge strip substantially filling the space between 20 the front and two ends of the covers, one end of which is provided with an inwardly turned hook, detachably locking it to the opposing hook of the locking plate, the opposite end of the locking plate being pro- 25 vided with a slot, a lock mounted upon the inner face of the adjacent end of the edge strip with its bolt registering with and adapted to be removably engaged with said slot, and a coin slot in the end edge strip 30 adjacent the lock, substantially as described.

9. A book-form savings bank comprising in combination a back and covers bent from a single sheet of metal with the opposing covers parallel and extending at a right

angle to the back, posts rigidly securing and 35 supporting said covers at their side edges provided with lugs projecting through and upset in the covers, one of which lugs is provided with a bend extending diagonally across the outer bottom corners of said 40 covers, an edge strip provided with inwardly projecting hooks detachably engaging the posts at the bottom and front edge of the covers, a hinged joint in the upper end of said edge strip pivotally connecting 45 the upper end edge strip with the lug of the front edge strip, and means for detachably locking the free ends of said edge strip with the back connecting the covers.

10. A book-form savings bank comprising 50 in combination a back, covers bent to form from a single sheet of metal, a sheet metal edge strip forming edges therefor provided with hooks, one at the side and the other at the bottom of the book, a metal strip 55 spacing and connecting the opposing covers of the book provided with a slot receiving said bottom hook, and a plate joining the longitudinal edges of said covers engaged by the upper hook.

In witness whereof, I have hereunto set my hand and affixed my seal this 29th day of May, A. D. 1912.
